ELECTRICAL CRYSTAL UNIT

Stephen L. Levy, Bedford, Mass., assignor to Sylvania Electric Products Inc., a corporation of Massachusetts

Application January 6, 1956, Serial No. 557,665

6 Claims. (Cl. 250—31)

The present invention relates to microwave apparatus, and more particularly to an improved coaxial crystal cartridge which may be employed as a rectifier, mixer and the like at microwave frequencies.

For the mixer of superheterodyne receivers used at microwave frequencies, it is common practice to employ a crystal diode, rather than a vacuum tube type mixer. Crystals, commonly although not necessarily silicon, afford more favorable signal to noise ratios than the triode or pentode mixers used at lower frequencies. Furthermore, crystals by reason of their small physical size and simple configuration are better suited to effective incorporation within waveguide or coaxial cable transmission systems.

In such systems wherein a crystal mixer is employed, it is necessary to provide suitable connections for the incoming signal (hereinafter termed the R. F. input), the oscillator signal (L. O. or local oscillator), and for the output signal (I. F. signal) resulting from the beating or mixing of the oscillator frequency with the signal frequency. In the conventional coaxial crystal cartridge, the crystal is secured to one face of a metal plug, termed the back plug, that is in direct metallic contact with the shell. The cat whisker that contacts the crystal is carried by a pin that extends through and is supported by an insulating bead fitting within the shell.

In such conventional cartridges, it is necessary to employ a mounting for the cartridge which enables the pin to serve as the input connection for the R. F. signal to the crystal, and also for the I. F. or video output from the crystal. This necessitates the use of an R. F. choke on the output arm of the mounting, to keep the R. F. signal out of the input to the I. F. or video amplifier. Since the choke is effective only over a relatively restricted frequency range, the use of an R. F. choke limits the frequency range over which the assembly is operative, so that broad band operation is not satisfactory.

In addition to the problems involved in the R. F. choke, the conventional crystal cartridge necessitates special provisions in the mounting for the separate I. F. output from the pin carrying the whisker. The conventional crystal mounting also presents connection problems when the crystal is to be used as a simple detector.

Many of the limitations and problems encountered in using the conventional type of mixer crystal cartridge in superheterodyne microwave receivers are avoided by using crystal cartridges of the type disclosed by Theodore S. Saad in application Serial No. 484,763, filed January 28, 1955, and assigned to the assignee of this invention. In the Saad application a crystal cartridge is disclosed which not only simplifies the mounting of the crystal in coaxial and waveguide systems but which also permits use of a wider range of operating frequencies. This is accomplished by insulating the metal plug holding the crystal from the metal shell of the cartridge so as to obtain a capacitance which will serve as a low impedance pass from the plug to the shell for the R. F. signal and allow

2

the I. F. output to be taken at the plug, thus eliminating the necessity of the R. F. choke at the I. F. output, and providing a crystal mixer capable of operating over a broader band of frequencies. A so-called D. C. return path for completing the I. F. circuit back to the center conductor or pin of the Saad cartridge may be afforded for example by extending the input probe connected to the center conductor to the walls of the waveguide. However, this has the disadvantage of either drastically reducing the operating bandwidth of the mixer or requiring manual tuning at the crystal cartridge input.

In the above mentioned Saad application a cartridge construction is disclosed which permits proper matching over a wide band of frequencies without tuning. This is accomplished by the use of a D. C. return located within the chamber defined by the shell, plug, and insulating bead, and generally is in the form of a small diameter wire extending directly between, and electrically connecting, the center conductor and the shell of the crystal cartridge. This arrangement has afforded excellent results for use at most frequencies at which the crystal cartridge itself is capable of satisfactory operation. However, it has been found that at lower incoming signal frequencies there is sufficient leakage of the signal via the D. C. return to cause appreciable attenuation of the signal reaching the crystal and taking part in the mixer action.

It is therefore an object of this invention to provide a coaxial crystal cartridge for use at microwave frequencies which makes possible simplified connection in a microwave system and which permits operation over a wide band of frequencies without objectionable variation with frequency of input signal strength at the crystal.

It is a feature of this invention to provide a coaxial crystal cartridge in which the R. F. input is isolated from the output, the cartridge incorporating a D. C. return path within the cartridge permitting operation in the lower portion of the range of frequencies for which the crystal is designed without excessive attenuation of the input signal.

A further feature of this invention is to provide a coaxial crystal cartridge in which an internal D. C. return path is provided to connect the center conductor and the shell of the cartridge, the path being of high impedance to reduce the loss of input signal at lower microwave frequencies.

The objects of this invention are achieved through certain adaptations and improvements of crystal cartridges of the type described in the Saad application. For example, although there is provided in the cartridges of the present invention a D. C. return path connecting the center conductor and the shell to complete the I. F. circuit associated with the crystal output, the return, instead of being a direct short-path connection, is in the form of a conductor element having appreciable inductive reactance even at lower microwave frequencies, which offers a high impedance to the input signals, thereby reducing the loss of signal strength through the D. C. return. Generally, the conductor element consists of a thin wire connected at one point to the center conductor of the cartridge and extending along a tortuous path, including at least one inductive turn, to a point of connection on the shell of the cartridge.

The foregoing and other objects and features of the invention will be best understood from the following description of particular embodiments of the invention, reference being had to the accompanying drawings wherein:

Fig. 1 is a sectional elevation view along line 1—1 of Fig. 2 on an enlarged scale showing the novel crystal cartridge construction of this invention.

Fig. 2 is a cross-sectional view of the device through line 2—2 of Fig. 1.

Fig. 3 is a sectional view in elevation along line 3—3

of Fig. 4 of a modification of the crystal cartridge of this invention mounted for use as a waveguide mixer.

Fig. 4 is a plan view of the arrangement shown in Fig. 3 in section along line 4—4 of Fig. 3.

Fig. 5 is a sectional view of a further modification of the crystal cartridge of the type contemplated by the present invention.

The embodiment of my invention shown in Figs. 1 and 2 is a coaxial crystal cartridge comprising a shell or outer conductor 10 in the form of a hollow cylinder. Fitting snugly within the shell is a cylindrical insulating bead or support 11 through which extends a center conductor pin 12. The pin has a reduced tip portion 13 at one end to facilitate telescoping connection with associated coaxial structure. The shell and the pin are of appropriate dimensions to permit connection for example to standard coaxial cable and holders. A resilient cat whisker 14 with a point for making rectifying contact with the crystal 16 is secured as by welding or soldering at the opposite end of pin 12 from the reduced portion 13. The crystal or semiconductor element 16, usually silicon at microwave frequencies, is supported by a cylindrical metallic back plug 15 to which the crystal is secured as for example, by soldering. The back plug is insulated from the cartridge shell by means of a layer or sleeve of insulating or dielectric material 20. Primarily to facilitate insertion of the back plug assembly including the dielectric layer into the shell a metallic ring or sleeve 17 is provided between the dielectric layer and the shell as shown. The plug and the sleeves 20 and 17 are suitably dimensioned so that the entire assembly fits snugly within the shell. The plug is provided with a suitable means for making an output connection. As shown in Fig. 1, recess 18 is provided to receive the center conductor of a coaxial connector. The plug and shell together with the dielectric layer form a condenser of appropriate capacitance to by-pass the R. F. signal from the crystal to the shell, but to act as a relatively high impedance to the I. F. signal from the crystal which is made available at connection means 18 in the plug.

A wire 19, which is an extension of the cat whisker 14 beyond the point at which the whisker is welded to the center conductor 12, extends in a tortuous path from its point of connection with the center conductor to a point of connection with the shell of the cartridge to serve as an internal D. C. return path for any microwave circuit in which the cartridge may be employed. Although the conductor element constituting the D. C. return may be of any configuration having proper inductance, I have found that from the standpoint of fabrication and assembly the D. C. return conductor element 19 shown in Figs. 1 and 2 as a flat spiral, offers distinct advantages. The end of wire 19 is bent at its point of contact with the shell and the end portion is held in position between the insulating bead and the shell. This connection is achieved at the time of assembly by arranging the D. C. return element properly on the insulating bead 11 and forcing the bead into the position in the shell as shown in Fig. 1.

Figs. 3 and 4 illustrate a modified form of the crystal cartridge of this invention mounted to operate as a mixer in a system employing rectangular waveguide. The crystal cartridge 30 is essentially similar to the device shown in Fig. 1 in that it includes a shell 31 enclosing a conductive back plug 34 and insulating bead 32 supporting, respectively, silicon crystal 36 and center conductor or pin 33 to which pointed cat whisker 37 is welded as shown. As in the device of Fig. 1 the plug and bead are spaced apart within the shell to afford suitable rectifying contact between the whisker point and the crystal. A recess 38 is provided in the back plug to afford connection for the I. F. output signal from the crystal. Unlike the cartridge shown in Fig. 1, the plug is separated from the shell only by the dielectric sleeve 35. In addition, the D. C. return element 39 includes only a single turn about the center conductor be-

tween its points of connection with the center conductor and shell. Still further, the return element, rather than being an extension of the cat whisker, is a separate length of wire welded or soldered at its terminal ends 39a and 39b to the central conductor and shell of the cartridge as best shown in Fig. 4.

The crystal cartridge 30 is mounted in a holder 40 which is attached as by welding to a section of waveguide 41. Flange 42 is provided for connecting the section of waveguide to the R. F. input and the local oscillator signal. A probe 43 is connected to the end of pin 33 and extends about half-way into the section of waveguide 41.

In operation the R. F. input signal and the local oscillator signal are fed into the rectangular waveguide at the flange 42. These input signals then pass via probe 43 into the crystal where the mixing or beating action takes place. As a result of this mixer action energy is presented at the back plug at the frequencies of the R. F. and local oscillator signals as well as the frequencies represented by the sum and difference of these signals. Usually the I. F. output signal of the cartridge taken at connection means 38 is at the frequency of the difference between the input signals. For example, assuming the cartridge 30 to be designed for operation with R. F. input frequencies in the range of 1,000 to 12,000 megacycles per second (mc. p. s.), the difference between the R. F. and local oscillator frequencies typically is of the order of 30 mc. p. s. By virtue of the capacitative effect afforded by the assembly of the back plug, the shell, and the dielectric layer 35, the energy of input signal and higher frequencies passes directly from the back plug to the shell. However, the value of this capacitance is such that the assembly offers a high impedance to the I. F. signal which is taken off a suitable connection at recess 38. Typically, for the range of frequencies referred to above, the capacitance of the plug, shell and dielectric layer assembly is of the order 7-12 μ uf.

Normally the I. F. output energy as it is employed in further stages (not shown) is connected through an impedance network to ground. It is likewise essential that a ground or return path be provided for the D. C. and low frequency products of the mixer action. In devices of the type disclosed in the above-discussed Saad application this has been accomplished by means of a short wire within the crystal cartridge interconnecting the center conductor and the shell of the cartridge. However, it has been found in employing cartridges of this type in systems involving input signals of lower microwave frequencies, e. g. 1,000 to 3,000 mc. p. s., that the input signals to the crystal are appreciably attenuated by loss through the return wire. Such attenuation is avoided in the arrangement shown in Fig. 3 by virtue of the novel configuration of the D. C. return element of wire 39 which is wound about the center conductor 33 in non-contacting spiral fashion to form at least one (as shown) or more complete turns or loops between its terminal connections at the center conductor and shell. Apparently the effect of this configuration of the wire is to produce sufficient inductive reactance in the D. C. return conductor so that appreciable impedance is offered to the flow of energy at signal frequencies as low as about 1,000 mc. p. s. In any event it has been observed that substantially improved signal to noise ratios are realized in cartridges employing my novel D. C. return as compared to cartridges in which a short path direct return is used.

It will be obvious from the above explanation that the precise configuration of the return conductor may be varied depending on the frequency of input signals involved. Thus, if a spiral arrangement is employed, it may be stated generally that an increase in the number of turns will effect a decrease in signal loss at lower frequencies. Within the requirements of this invention, the cross-sectional shape or area of the return conductor has not been found to be critical. However, wire of from

1.5 to 2.5 mils diameter has been found to be generally compatible with the small space normally available in crystal cartridges of the type contemplated by this invention. Preferably the return element is in the form of a flat spiral arranged within the shell with the central conductor generally at the origin or center of the spiral.

In the crystal cartridges shown in Figs. 1, 2, 3, and 4 the cat whisker is supported on the center conductor to which the input signal is applied. It may be desired to interchange the positions of the cat whisker and crystal as illustrated by the crystal cartridge shown in Fig. 5. In this case the crystal 56 is soldered to the inner end of center conductor 54 while the cat whisker 57 is carried by the back plug 51 which again is insulated from shell 50 by dielectric layer or sleeve 52. The return conductor element 53 is shown as a flat spiral similar to the D. C. return element of the device of Fig. 1. However, in this arrangement the return wire obviously cannot be an extension of the cat whisker. As shown in Fig. 5 it is a separate length of wire welded at one end to the center conductor and secured in contact with the shell at its other end by the tight fit of the insulating bead 55 against the shell. The return element in this case functions in the same manner as the corresponding elements in Figs. 1, 2, and 3 in affording a path for return of the D. C. component of the input signals to the shell of the cartridge.

It should also be understood that Fig. 3 shows only one of the possible applications of this invention. The crystal cartridge has other uses which will be obvious from the foregoing explanation of the invention, for example, as a mixer in a coaxial line or as a video detector. Some of these applications are shown in the aforementioned Saad application.

What I claim is:

1. A crystal cartridge comprising an outer conductor, cooperating semiconductor and rectifying connection elements, means supporting said cooperating elements in fixed position with respect to said outer conductor, and means providing a direct current path from one of said elements to said outer conductor including a conductor element having at least one inductive turn in its length.

2. A crystal cartridge for microwave apparatus comprising a semiconductor element, an outer conductor, means for supporting the semiconductor element in fixed position with respect to the outer conductor, an inner conductor having means making rectifying connection with said semiconductor element, and a direct current

return element extending in a tortuous path between, and electrically connecting, said inner and outer conductors.

3. A crystal cartridge for microwave apparatus comprising a conductive outer shell, cooperating crystal and cat-whisker elements within the shell, a first conductive support on which one of said elements is mounted, a second conductive support on which the other of said elements is mounted, means for holding said supports in said shell in position to obtain rectifying contact between the supported elements, and a direct current return element comprising a conductor having an inductive turn electrically connecting the shell with one of said supports.
4. A coaxial crystal cartridge comprising a conductive shell, a conductive plug within the shell, a layer of dielectric material between the plug and the shell, a crystal mounted on said plug, an insulating support also within said shell and spaced from said plug, a pin extending through and fixed in position by said insulating support, a catwhisker secured to said pin and in rectifying contact with the crystal, and a direct current return element extending in a tortuous path between, and electrically connecting, the shell and the catwhisker.
5. A coaxial crystal cartridge comprising a conductive cylindrical shell, a conductive back plug within the shell, a sleeve of dielectric material between the shell and plug, an insulating bead also within the shell and spaced axially from said plug, a central conductor secured axially in said bead with end portions on opposite sides thereof, a crystal mounted on said plug, a catwhisker secured to an end portion of said central conductor and in rectifying contact with the crystal, and a direct current return element electrically connecting said central conductor to the shell and extending in a spiral path from its point of connection with the central conductor to its point of connection with the shell.
6. A coaxial crystal cartridge as in claim 5 in which said return element is located between the plug and bead and is in the form of a flat spiral conductor arranged with the central conductor generally at the origin of the spiral.
